UNITED STATES PATENT OFFICE.

WILLIAM WEIR HENRY, OF WOLLASTON, MASSACHUSETTS, ASSIGNOR TO S. H. COUCH CO. INC., OF ATLANTIC, MASSACHUSETTS.

INTERCOMMUNICATING TELEPHONE.

1,130,971.

Specification of Letters Patent.

Patented Mar. 9, 1915.

Application filed June 19, 1914. Serial No. 846,152.

To all whom it may concern:

Be it known that I, WILLIAM WEIR HENRY, a citizen of the United States, residing at Wollaston, in the county of Norfolk and State of Massachusetts, have invented certain new and useful Improvements in Intercommunicating Telephones, of which the following is a specification.

This invention relates to telephones of the inter-communicating type and has special reference to the assembling of all the mechanism connected with the various circuits upon and within a formed block composed of insulating material, which block, being secured against and partially within a wall-plate formed of sheet metal, renders possible the making up of a very compact and serviceable unit where economy of space and low cost are desirable. This block, which is preferably molded, has the gong mountings and cord bushing formed integral therewith, and these serve as pilots for quick assembly upon the pressed wall-plate. Also, the various terminals, the bus-bar and the bell-magnet frame are lodged within close-fitting recesses formed in the block and thus but one fastening bolt is required for each piece. Other advantages, both of construction and use, will appear in the detailed description of the illustrated embodiment of my invention which accompanies and forms part of this specification, and in which—

Figure 1 is a front view of one of my complete units. Fig. 2 is a sectional elevation on line 2—2 of Fig. 1. Fig. 3 is a rear view, with box cover removed. Fig. 4 is a sectional elevation on line 4—4 of Fig. 3. Fig. 5 is a sectional elevation on line 5—5 of Fig. 3. Figs. 6 and 7 are, respectively, rear and front views of the molded block. Fig. 8 is a front view of the pressed wall-plate. Figs. 9, 10 and 11 are sections on the various lines 9—9, 10—10 and 11—11 of Figs. 6 and 7. Fig. 12 is a detail.

The wall-plate 1, preferably of sheet brass, is molded or stamped to give the appearance of a flat plat of added thickness, with beveled edges 2 and countersunk screw holes 3 and 4, the former, 3, being adapted to receive screws 5 which secure the entire unit telephone to the wall of a building, and the latter, 4, being adapted to receive bolts 6 for securing the molded block 10 to plate 1. In addition to the countersunk openings 3 and 4, plate 1 has a number of other open-

ings punched therethrough which will be referred to in detail. These are best illustrated in Fig. 8 and comprise a large central opening 11 for the transmitter, two smaller openings 12 for the gong-posts 20 on block 10. A hole 13 is provided for the projection therethrough of the cord bushing 21 on block 10, whereby the said block is quickly and accurately fitted to plate 1, ready to receive the fastening bolts 6 and also two others 7 which pass through holes 14 in plate 1 and assist in securing the block to the plate. Near the bottom of plate 1 are shown two round holes 15 adapted for the projection therethrough of the push buttons 22 and 23. Above holes 15, I form a pair of rectangular openings 16 in plate 1 so as to reveal the lettered portions of a strip 24 which is concealed behind the plate. A slot 17, to the left of openings 15, permits the play of hook 25 therein, in a usual manner. Near the top of plate 1, I form an opening 18 for the clapper-stem 26 and, above and below, this opening 18 is enlarged, as at 19, to permit the securing in place of a clapper-guard 27, as will be later explained.

Referring now to Figs. 6, 7, 9, 10 and 11, and incidentally to Figs. 3 and 4, block 10 has, in addition to the large central opening 30, a series of recesses on both faces and on the two long edges, which will now be referred to in detail. On the rear face, Fig. 6, the recesses 31 are adapted to receive the line terminals 32 and 33 (but two of the latter being shown) and recesses 34 are formed to receive the ringing terminals 35 and 36, (but two being shown.) Bus-bar 37 is adapted to fill recess 38, the switch base plate 39 is seated in recess 40 and the magnet base 41 occupies recess 42. There is also a recess 43 for housing the receiver cord 44 and two countersunk through openings 45 for securing the transmitter to block 10. On the front of block 10, Fig. 7, will first be noticed a large recess 50 for housing certain bolt heads and connectors, a flat, rectangular recess 51 for the strip 24, a recess 52 for the switch bolt and the recess 53 in gong-posts 20, by means of which the gongs 55 are secured by screws 56. At the sides of block 10, I preferably form two shallow recesses 57 to receive the spring clips 58 on the cover box 59. In addition to the recesses and holes noted, block 10 is also

formed with through holes 60 for the push buttons 22 and 23, the slot 61 for hook 25, the opening 62 for cord 44, the hole 63 for the clapper stem and the various bolt holes 5 for securing the terminal plates, bus-bar, switch base and bell magnet frame in place. The bell magnet 65 is secured to the frame 41, the switch 66 is mounted on switch base 39 and a ground wire terminal 67 is provided in bus-bar 37.

The specific form of wiring illustrated need not be described in detail, as the only feature of novelty therein contained is that of inter-changeability, whereby the circuits 15 may be altered to produce various results without changing the form of insulated block 10. As noticed, provision is made for three terminals for each of sockets 31 and 34, where but two are illustrated, but in this 20 case, I make use of one of the openings 60 for a fastening bolt 6. An ordinary receiver 70 is indicated in Fig. 1.

The clapper guard 27 is formed with two bent ears 71 adapted for insertion through 25 openings 19 and after block 10 is assembled upon plate 1, guard 27 is locked in position.

By making wall plate 1 of pressed metal, a new form of attachment for the transmitter is necessary, that illustrated being described as follows:—The transmitter 71 is mounted upon a bridge 72, the feet of which are adapted to lie within the opening 11 in plate 1. The diaphragm 73, which is 35 slightly larger in diameter than the opening 11, is mounted in front of the bridge 72 and also plate 1 and is held in place by a spun disk 74 which carries a threaded socket for an ordinary mouth-piece 75. 40 Back of the feet of bridge 72 and thus inside or back of wall plate 1 I mount an annular ring 76, the difference of whose two radii spans the periphery of opening 11. Bolts 77 passing through disk 74, diaphragm 45 73, the feet of bridge 72, which may be slotted, and ring 76 hold all firmly in place, the bolts lying within opening 11 but adjacent to the edge thereof. In addition to bolts 77, I prefer to screw the transmitter mechanism independently to block 10 by screws 78, set in openings 45 and screw threaded into ring 76.

The terminals 32 and 33 are held in place by screws 80, both of which, (as well as the 55 third one, not shown) are adapted at their rear ends to alternately receive a metal strap 81 for electrical connection with bolt 82 which secures the magnet frame. Strip 81, seen best in Fig. 12, has a slotted hole at one 60 end to accommodate itself to the varying radii of alternative attachments. This adjustment permits of modifications in wiring without changing the parts. Bolts 85 secure terminals 35 and 36 to block 10 and 65 bolt 86 similarly fastens bus-bar 37 in place.

Bolt 87 is for the purpose of securing switch base 39.

The house wires are indicated at 90, Fig. 2, but are omitted in the other views as not offering any feature of novelty.

By the above description, it will be noticed that my unit, by its compactness, is well adapted for use in thin partition walls where it is desirable to provide a box which shall not project therefrom unduly, and, when mounted, the wall plate 1 has every appearance of solidity and the general neatness and finish of the exposed parts provides an appearance which might be classed with wall ornaments. Again, by providing a molded insulated block, the ease and certainty of assembling and the lessened liability to any disarrangement of the parts furnish a unit which represents the most advanced state of the art known to me.

I do not limit myself to the precise form of construction shown.

What I claim is:—

1. In telephones of the inter-communicating type, a wall plate so formed of thin material as to give the appearance of a flat plate of added thickness and a molded block of insulating material adapted to be secured to and partially within said wall plate, said block being provided with integrally formed 90 gong support and cord bushing adapted to protrude through suitable, close-fitting openings in said wall plate; in combination with means for attaching said block to said wall plate.

2. In telephones of the inter-communicating type, a wall plate so formed of thin material as to give the appearance of a flat plate of added thickness and a formed block of insulating material adapted to be secured to and partially within said wall plate, said block being provided with integrally formed 95 gong support and cord bushing adapted to protrude through suitable, close-fitting openings in said wall plate, and means for attaching said block to said wall plate; in combination with a cover box of thin material and provided with a plurality of spring snaps adapted to automatically engage suitable recesses in said block for the purpose of 100 uniting said block and said box.

3. In telephones of the inter-communicating type, a molded block of insulating material and provided with a variety of recesses and bolt holes, the former adapted to snugly receive and hold against lateral movement a series of metal connectors and the latter, one for each connector, being adapted to house the bolts for retaining said connectors within said recesses, a wall plate adapted for 110 mounting on said block and provided with close-fitting openings for suitable gong-support and cord bushing, and suitable gong-support and cord bushing integrally formed on said block and adapted to project through 115 120 125 130

said openings; in combination with means for securing said block to said wall plate.

4. In telephones of the inter-communicating type, a wall plate of sheet metal and provided with a suitable opening for mounting the transmitter mechanism, a spun metal disk adapted to receive the mouth-piece, the diameter of said disk being larger than the diameter of said opening, and an annular ring, the difference of whose radii spans the periphery of said opening, said disk and said ring being adapted for mounting on opposite surfaces of said wall plate and over said opening, thereby inclosing the mountings for said transmitter mechanism; in combination with bolts for uniting and clamping the whole together, said bolts being so positioned as to pass through said disk and said ring and said opening, thereby engaging the periphery of the latter to prevent lateral movement of said disk with respect to said opening.

5. In telephones of the inter-communicating type, a wall plate of sheet metal and provided with a suitable opening for mounting the transmitter mechanism, means whereby said transmitter mechanism may be mounted on said wall plate and secured against lateral or perpendicular movement with respect to said plate, and a formed block of insulating material and adapted for the mounting thereon of the switch, bell-magnet and connectors, means for detachably securing said block to said wall plate, and means for securing said transmitter mechanism against rotation with respect to

said plate, said means comprising an attachment between said block and said transmitter mountings.

6. In telephones of the inter-communicating type, a wall plate of sheet metal provided with an opening for mounting the bell clapper guard, a formed block of insulating material and adapted for the mounting thereon of the bell-magnet, switch and connectors, means for securing said block to said wall plate, and a bell clapper guard provided with two bent ears adapted to engage said opening, and means whereby said guard is held against removal through the agency of said first means.

7. In telephones of the inter-communicating type, a formed block of insulating material provided with recesses and bolt holes, the former adapted to hold suitable terminals, magnet and switch mountings against lateral movement with respect to said block, the latter, one for each of said recesses, being adapted to house certain bolts which may be used to prevent perpendicular movement of said terminals, magnet and switch mountings with respect to said block, and bosses, adapted for the support of a suitable gong and for the passage of the cord, said bosses being formed integral with said block.

In testimony whereof, I have affixed my signature, in the presence of two witnesses.

WILLIAM WEIR HENRY.
